US00D993601S

(12) **United States Design Patent** (10) Patent No.: **US D993,601 S**
(45) Date of Patent: **** Aug. 1, 2023**

(54) **SHOE UPPER COMPONENT**

(71) Applicant: **Skechers U.S.A., Inc. II**, Manhattan Beach, CA (US)

(72) Inventors: **Eric Chi Chiang Wang**, Redondo Beach, CA (US); **Hui Xie**, Dongguan (CN); **WanLing Cheng**, TaiChung (TW)

(73) Assignee: **Skechers U.S.A., Inc. II**, Manhattan Beach, CA (US)

(**) Term: **15 Years**

(21) Appl. No.: **29/888,982**

(22) Filed: **Apr. 6, 2023**

(51) LOC (14) Cl. **02-04**

(52) U.S. Cl. **D2/946**
USPC ....

(58) **Field of Classification Search**

USPC D2/929, 930, 932, 946, 971, 972
CPC A43B 3/00; A43B 21/24; A43B 17/02;
A43B 3/122; A43B 3/12; A43B 3/0036;
A43B 9/14

(57) **CLAIM**

The ornamental design for a shoe upper component, as shown and described.

DESCRIPTION

FIG. 1 is a front perspective view of a shoe upper component in accordance with my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view of the shoe upper component with environment removed;

FIG. 9 is a front elevation view thereof;

FIG. 10 is a rear elevation view thereof;

FIG. 11 is left side elevation view thereof;

FIG. 12 is right side elevation view thereof;

FIG. 13 is a top plan view thereof; and,

FIG. 14 is a bottom plan view thereof.

Broken lines showing the remainder of the shoe in the figures are for illustrative purposes only and form no part of the claimed design. The surfaces devoid of shading lines form no part of the claimed design.

1 Claim, 11 Drawing Sheets
